CONTAINER UNIT AND CARRIER FOR MULTIPLE UNITS

Robert O. Duff, Jr., Boston, Mass., assignor to Container Corporation of America, Chicago, Ill., a corporation of Delaware

Application February 1, 1955, Serial No. 485,389

10 Claims. (Cl. 229—15)

The invention relates to packaging devices composed of relatively strong but light weight and inexpensive materials such as paperboard and, more particularly, to packaging devices especially useful in packing, storing, shipping and otherwise handling a multiple number of individual packages or containers of merchandise as a single package or unit and to unit containers adapted for unit handling of multiples thereof. Packaging devices of a type embodying the invention have been employed very successfully in packaging, shipping and storing dressed poultry.

Among the primary objects of the invention is the provision of a container of such special construction that it will serve adequately as a secure unit package for a particular commodity and yet may be assembled and secured together with another similar package or two or more additional similar packages in what may be termed a carrier member so that the several unit package or containers collectively with the carrier will form a multiple or compound package unit.

Another of the primary objects is to provide a carrier member so constructed and arranged as to interlock with one or a plurality of individual container units thereby to constitute a strong and easily transported compound unit but which will permit ready unlocking and removal of any or all of the container units as may be desired.

Still another object of importance is to provide a simple yet highly effective locking means by which the closure members of each individual or unit container may be secured in closed position relative to such unit container when the container is apart from the carrier as well as when the unit container is connected or assembled singly or in multiple numbers with the carrier, the locking means being such as to function both to secure the closure member of a unit container and the unit container to the carrier at one and the same time.

A further object is to provide an efficient and effective locking device which may be applied to the carrier as well as to the unit containers and of such nature that it may be employed to cooperate with and to aid the locking means of the unit container in securing the closure of the unit container in closed position and simultaneously securing the unit container to the carrier. In this connection it should be stated that the invention provides a unique type of container locking means by which the carrier and each and every individual or unit container may be firmly and securely interlocked for handling purposes but in such manner that each of the unit containers is subject to immediate selective release from the carrier for separate handling or for opening the unit closure for inspection or other access to the container contents.

Many other objects as well as the uses and advantages of the invention will be appreciated after reading the following description and claims and after viewing the drawings in which:

Fig. 1 is a perspective view of the presently preferred

2

embodiment of the invention, the view representing an assembly of three individual or unit containers fully locked in its place in the carrier, a second unit container in place in the carrier with the closure and locking means in position for locking to the carrier, and the third unit container in a position where it is about to be placed in the carrier, the view showing the closure members in open position;

Fig. 2 is a fragmentary end elevation of the combined container and carrier shown at the left in Fig. 1 with the locking means released;

Fig. 3 is a sectional view through the carrier and a container wall, the view representing a section taken along section line 3—3 of Fig. 2;

Fig. 4 is a vertical section through one of the side walls of a carrier and the adjacent end wall and locking flap of the container showing a double locking arrangement, the view being taken along section line 4—4 of Fig. 1;

Fig. 5 is a sectional view taken along the section line shown in Fig. 4, looking in the direction indicated by arrows 5—5;

Fig. 6 is another sectional view taken along the section line shown in Fig. 4, looking in the direction indicated by the arrows 6—6;

Fig. 7 is a plan view of a blank for a preferred type of container to be used with the carrier; and

Fig. 8 is a plan view of a blank for a preferred type of carrier.

The drawings reveal, in Figs. 1 and 7, the construction of the presently preferred individual container units which have been employed with the likewise presently preferred type of carrier construction also shown in Fig. 1 in combination with containers and in blank form in Fig. 8. However, as will become apparent, both the container and the carrier may be varied over wide ranges of construction while embodying the invention.

Essentially, the packaging device illustrating the invention consists of three unit containers each of hexagonal form, equal in their respectively corresponding dimensions, and otherwise of like construction, and a trough or U-shaped carrier of such width, height and length and general conformation as to receive and embrace the three unit containers in snugly nested arrangement therein. Of course, the carrier may be constructed to receive only two or it may embrace four or more unit containers, as may be desired, these specifications depending upon various factors including the size and weight of commodities to be packaged, the strength of the materials of which the containers and carriers are made, the purpose or use to be made of the combined units and carriers, etc.

The unit container blank shown in Fig. 7 which may be cut from any suitable paperboard, corrugated or otherwise, is generally rectangular in outline. It is cut and scored to provide like side panels 11 and 12 of equal size, similar end panels 13 and 14, a glue or securing flap 15 by which the blank ends are to be connected, bottom forming flaps 16, 17, 18 and 19, a top closure flap or member 21, and a second top closure flap or member 22 which, at each of its opposite ends carries what will be termed a locking or securing flap 23. Top and bottom edges of the side panels 11 and 12 are defined by the parallel scores 24, 25 and 24', 25' and the bottom edges of end panels 13 and 14 are defined by scores 26 and 26' aligned with the scores 25, 25'. The vertical edges of the side and end panels and glue flap 15 are defined by parallel scores 27 so that when the blank is folded along such scores it forms a rectangular tube, the flap 15 being secured flat against the inner or outer face of end panel 14 by adhesive or staples or other fastening means.

After the tube has been formed as above described

it may be flattened by folding one end panel and one side panel against the respectively adjacent side and end panels for stacking and shipping in bundles or otherwise, ready to be set-up or erected from such collapsed condition at the place of use. As will be recognized, the several bottom closure flaps in this example are formed to provide an automatic lock of the well known "Houghland" type, effective in the process of setting-up the container from the flattened state by first folding inward the side flap 16 having the notch in its edge, next folding in the two end flaps 17 and 19 and, finally, folding inward the other side flap 18 the projecting tongue of which snaps through the notch in the opposite side flap and lodges against the inside face thereof.

The upper edge of each of end wall panels preferably is notched, as indicated at 28, to a depth substantially equal to the thickness of the material of which the container is composed, each of these edges at its end closest to the end edge of closure member 21 (in the set-up condition of the container), preferably being sloped down gradually to the full depth and terminating in an abrupt shoulder 29 at a distance from the respective junctures of the side wall 11 with the end walls 13 and 14, equal to the width of the closure member 21. The purpose of this arrangement is to permit the top surface of the closure member 21 to be flush with the top edge portions 30 over that portion of the container top which will be covered by the other closure member 22. It will be noted that each end edge 31 of the closure member 21 projects slightly beyond the respectively adjacent score 27—the amount preferably being equal to or a little more than a thickness of the material—so that it may rest upon the top edge 28 of each end wall. Each of end wall panels 13 and 14 has an opening 32 of rectangular shape and particular dimensions and location, for purposes to be described.

The closure member 22 preferably has a width, measured normal to the crease score 24', that will permit it to lap the closure 21 to the beginning of the upward slope of each edge 28, a position slightly beyond the upwardly projected position of the edge 33 defining one end of each opening 32. Each of the locking or securing flaps 23 preferably is delineated from the closure member 22 by a pair of crease scores 34, 34' parallel to scores 27, the scores 34', at least, being spaced outward from the respectively adjacent scores by an amount substantially equal to one thickness of the material although it may be desirable, in certain instances, to have this amount equal to one thickness of the material of which the container is made plus the thickness of the material of which the carrier is made.

Each securing or locking flap 23 terminates in an integral locking tab generally designated L and each in construction and function is similar to the other. Each tab L is joined to its flap 23 along a score 35 which is parallel to and spaced from score 34' by a distance substantially equal to the perpendicular distance between the upper surface of the closure member 21 when disposed in the recesses of the upper edges of end wall panels 13 and 14 and the edge 36 defining the upper edge boundary of the adjacent end wall opening 32. At each end of score 35 the edges of each tab L are notched, as indicated at 37, to equal depths and so that the distance between opposite notch bottoms is substantially equal to or slightly less than the distance from the edge 33 of opening 32 to the opposite edge, the width of each tab L between its side edges being made greater than the distance between said end edges of opening 32 preferably by an amount equal to about two thicknesses of the material. The width of each notch 37 measured normal to the score 35 will be substantially equal to or slightly greater than two thicknesses of the material of which the container is made if containers and the carrier are composed of the same gauge of material, for reasons which will appear. Centrally of the outer free edge of each locking tab is a semi circular finger notch 38 and extending diagonally from

points near the junction of the arcuate edge of the notch 38 with the outer free edge of the tab to the bases of the notches 37 are scores 39. The tab dimension measured normal to the score 35 preferably is slightly less than the vertical dimension between the upper edge 36 and the opposite edge of opening 32.

Thus constructed the container is easily erected, closed and releasably but securely locked as will be apparent. After closure member 21 has been swung down about crease score 24 to lie in recess 28, the other top closure member 22 is swung down about crease score 24' to rest upon the upper surface of closure member 21 in which position the locking flaps 23 and locking tabs L may appear somewhat after the manner illustrated by the container in the center, Fig. 1. From such position the locking flaps are swung down about crease scores 34' to positions parallel to the end wall panels when the free or outer ends of the locking tabs L may be pushed through the openings 32, the tabs L swinging about crease scores 35 and the opposite outer corner portions of the tabs buckling along scores 39 to permit the tabs to pass the edges of the opening. The inward movement of the tabs is continued until the edge 33 and the edge opposite thereto have entered the opposed notches 37 at which time the closure is effectively locked in closed position. To effect release of the closure it is only necessary to insert a finger into the opening 32 and through the notch 38 and pull outward upon the tab.

The carrier, as each container preferably is made and as shown in Fig. 8, is composed of a single integral rectangular sheet of material such as paperboard which is scored along spaced parallel score lines 41, 42 to provide a base or bottom panel 43 and a side panel 44 at each side thereof. The distance between scores 41, 42, that is, the width of the bottom panel 43, will be equal to the overall length of the containers to be carried as measured between the outer surfaces of the container end walls 13 and 14. The length of the bottom panel 43 preferably will be equal to the product of the number of containers to be carried times the overall width of a container between the outside surfaces of its side walls 11 and 12, assuming that the containers are of equal size. The height of each side wall panel 44, as measured normal to the scores 41, 42, preferably is slightly less than or, at most, equal to the overall distance between the bottom of one of the containers and the edge 30 or, approximately, the height of an end wall panel 13 or 14 of a container so that the upper edges 45 of the carrier side walls will lie, preferably, a short distance below but not higher than flush with the container edges 30 and the adjacent top surfaces of the inner closure members 21 when the containers are in place within the carrier.

Each carrier side wall has one rectangular opening for each container, such opening being positioned to register with the adjacent opening in the container end wall 55 although it is preferable that such opening be slightly larger in its horizontal dimension in the plane of the wall than the corresponding dimension of the opening in the container end wall. Preferably also, each opening in the carrier side walls is normally closed by a locking tab M which is similar to the locking tabs L in construction and function, each being cut free from the carrier wall about three sides as indicated by the full lines 46 and hinged to the wall along its fourth side or bottom 60 along an horizontal edge score as indicated by the dot-dash line 47. These locking tabs M are also notched as at 48 at their corners adjacent to the hinge scores 47 to a depth such that the distance between the bottoms of opposed notches 48 of a tab M will be slightly less than the distance between a container opening edge 33 and the opposite edge, while the width of each such notch measured normal to the score line 47 will be equal to or slightly greater than one thickness of the material of which the container is made. After the manner of preparation of tabs L, the tabs M are notched as at 49

to provide finger openings and scored diagonally as at 50 to permit buckling of the tab as it is pushed through the opening in the adjacent container end wall.

Double security, if needed, is provided by the locking tabs M which will be pushed inward through the container end wall openings 32 where the corner edges at the notches 48 will engage the inner face of the container end wall 13 or 14, as the case may be, to secure the tab from releasing and returning to its original position. The tabs M are also intended to obstruct the outward movement of the tabs L by engaging them in end edge to side abutment after the manner illustrated in Fig. 4. However it is a simple matter to release and remove any desired container from the carrier by first pulling out the carrier locking tabs M through the openings in the particular container end walls and thereafter releasing the tabs L of such container. After the container is released the closure member 22 may again be closed and relocked thereby to provide a closed unit.

In the ordinary use of the container-carrier combination, the packed containers are closed to the extent of folding down each closure member 21 and then folding the closure members 22 over and down upon the members 21 but the flaps 23 are permitted to project outward at each end of each container. A container is then placed within the carrier with the openings in its end walls in register with opposed openings in the opposite side walls of the carrier whereupon the end flaps 23 are folded down about the scores 34' (or 34, 34') to positions to and against the outside surfaces of the carrier side walls to bring the locking tabs L into register with the respective openings.

When the tabs L are in such registering position they lie outside of the locking tabs M so that by pushing the opposed tabs L toward one another they are moved against tabs M displacing tabs M inwardly through the openings 32 at the same time that the tabs L are forced through the openings into the container. In this operation the diagonal scores of the tabs L and M permit the tabs to buckle enough to pass through the openings but the inherent resilience of the fibrous material causes the tab side edges to return to their initial positions thereby to lock the tabs in their inset positions. Since the natural movements of the hands and fingers of a person performing the above described operations will drive the tabs L inward to positions substantially at right angles to the side walls of container and carrier before the tabs are released by removal of the hands the tabs L will pass the tabs M on the inward movement and the latter will tend to spring upward to the position shown in Fig. 4 to bring their free outer edges into abutment against the outer surfaces of tabs L. Of course the tabs M may be omitted where the double locking security is deemed to be unnecessary, in which case reliance for security will be placed solely upon tabs L.

The close nested arrangement of the several containers within one carrier with each container side wall abutted relatively close against the adjacent container or containers together with the arrangement of the flaps 23 and locking tabs L which tend to draw the carrier and container bottoms tightly against one another, produce a very rigid structure so that a number of heavily loaded containers may be handled as one when placed in a carrier. The arrangement not only facilitates handling, storing and shipping certain types of commodities such as dressed poultry but effects substantial economies as will be appreciated.

While I have illustrated and described what presently are a preferred container unit, a preferred carrier and a preferred combination arrangement, other container units, carriers and satisfactory combinations may be devised without departing from the invention spirit and the scope of the appended claims.

I claim:

1. A unitary package for merchandise composed from

sheet material such as paperboard and comprising a plurality of independent containers and a carrier member releasably secured to each of the containers, said carrier member including a bottom panel and spaced upstanding side panels at opposite sides of the bottom panel, each of said side panels having apertures therethrough at locations between the top and bottom edges of such panel and in spaced relation to one another between the panel ends, each of said independent containers being substantially of hexahedral form and including a bottom wall, two pairs of opposed side walls and a top wall formed as a closure, one of one pair of opposed side walls being disposed substantially in face-to-face adjacent relation to one and the other to the other of the opposed inner faces of the side panels of the carrier member, each of said one pair of opposed walls of each independent container having an aperture substantially in register with an aperture in the carrier side panel to which it is adjacent, each of said container closure members extending from one carrier side panel to the other and having opposite end portions extending across the upper edges of the respectively adjacent side walls of such container and the adjacent upper edges of the carrier side panels, and locking means carried by each of said opposite end portions of each

closure member and disposed through the adjacent pair of registering apertures and in locking engagement with the adjacent side wall of such container.

2. A unitary package for merchandise composed from sheet material such as paperboard and comprising a plurality of independent containers and a carrier member releasably secured to each of the containers, said carrier member including a bottom panel and spaced upstanding side panels at opposite sides of the bottom panel, each of said side panels having apertures therethrough at locations between the top and bottom edges of such panel and in spaced relation to one another between the panel ends, each of said independent containers being substantially of hexahedral form and including a bottom wall, two pairs of opposed side walls and a top wall formed as a closure and having hinged connection with one of the side walls along a hinge axis extending transverse to the side panels of the carrier, one of one pair of opposed side walls being disposed substantially in face-to-face adjacent relation to one and the other to the other of the opposed inner faces of the side panels of the carrier member, each of said one pair of opposed walls of each independent container having an aperture substantially in register with an aperture in the carrier side panel to which it is adjacent, each of said container closure members extending from one carrier side panel to the other and having opposite end portions extending across the upper edges of the respectively adjacent side walls of such container and the adjacent upper edges of the carrier side panels, and locking means carried by each of said opposite end portions of each closure member and disposed through the adjacent pair of registering apertures and in locking engagement with the adjacent side wall of such container.

3. A unitary package for merchandise composed from sheet material such as paperboard and comprising a plurality of independent containers and a carrier member releasably secured to each of the containers, said carrier member including a bottom panel and spaced upstanding side panels at opposite sides of the bottom panel, each of said side panels having apertures therethrough at locations between the top and bottom edges of such panel and in spaced relation to one another between the panel ends, each of said independent containers including a bottom wall, two pairs of opposed side walls and a top wall formed as a closure and having hinged connection with one of the side walls along an axis extending transverse to and between the carrier side panels, one of one pair of opposed side walls being disposed substantially in face-to-face adjacent relation to one and the other to the other of the opposed inner faces of the

side panels of the carrier member, each of said one pair of opposed walls of each independent container having an aperture substantially in register with an aperture in the carrier side panel to which it is adjacent, each of said container closure members extending from one carrier side panel to the other and having opposite end portions extending across the upper edges of the respectively adjacent side walls of such container and the adjacent upper edges of the carrier side panels, and locking means carried by each of said opposite end portions of each closure member and disposed through the adjacent pair of registering apertures and in locking engagement with the adjacent side wall of such container.

4. A unitary package for merchandise composed from sheet material such as paperboard and comprising a plurality of independent containers and a carrier member releasably secured to each of the containers, said carrier member including a bottom panel and spaced upstanding side panels at opposite sides of the bottom panel, each of said side panels having apertures therethrough at locations between the top and bottom edges of such panel and in spaced relation to one another between the panel end, each of said independent containers being substantially of hexahedral form and including a bottom wall, two pairs of opposed side walls and a top wall formed as a closure, one of one pair of opposed side walls being disposed substantially in face-to-face adjacent relation to one and the other to the other of the opposed inner faces of the side panels of the carrier member, each of said one pair of opposed walls of each independent container having an aperture substantially in register with an aperture in the carrier side panel to which it is adjacent, each of said container closure members extending from one carrier side panel to the other and having opposite end portions extending outwardly across the upper edges of the respectively adjacent side walls of such container and outwardly across and thence downwardly below the adjacent upper edges of the carrier side panels, and locking means carried by each of said opposite end portions of each closure member and projecting through the adjacent pair of registering apertures and in locking engagement with the adjacent side wall of such container.

5. A unitary package composed of sheet material such as paperboard and comprising a plurality of individual merchandise containers and a carrier member common to all of the containers for the simultaneous support thereof, the carrier member including a generally rectangular bottom support panel and connected side panels extending upward in spaced relation to one another from a pair of opposite edges of the bottom panel, each of the side panels having a series of openings therethrough in spaced relation to one another and to the bounding edges of the panel, each of the containers being disposed upon said bottom panel between the side panels and each having substantially opposite side wall portions one of which is disposed adjacent to one of the carrier side panels and the other of which is disposed adjacent to the other side panel of the carrier, each of said container wall portions having an opening in register with one of the openings in the adjacent side panel, and means carried by each container and extending about the upper portion of the carrier side panels and projecting through the adjacent registering openings in the side panel and side wall portions for interlocking the containers and carrier.

6. A unitary package composed of sheet material such as paperboard and comprising a plurality of individual merchandise containers and a carrier member common to all of the containers for the simultaneous support thereof, the carrier member including a generally rectangular bottom support panel and connected side panels extending upward in spaced relation to one another from a pair of opposite edges of the bottom panel, each of the side panels having a series of openings therethrough in spaced relation to one another and to the bounding edges of the panel, each of the containers being supported upon said

bottom panel between the side panels and each having substantially opposite side wall portions one of which is disposed substantially in face-to-face abutting relation with the inner face of one of the carrier side panels and the other of which is disposed in similar relation with the inner face of the other side panel of the carrier, each of said container wall portions having an opening in register with one of the openings in the adjacent side panel, cover means carried by each container, and means attached to said cover means adjacent to each of said opposite wall portions of each container and extending over the adjacent upper edge portion of the carrier side panels and projecting through the adjacent registering openings in the side panel and side wall portion for interlocking the containers and carrier.

7. A unitary package composed of sheet material such as paperboard and comprising a plurality of individual and independent merchandise containers and a carrier member common to all of the containers for the simultaneous support thereof, the carrier member including an elongated bottom support panel providing a pair of relatively parallel edges extending lengthwise thereof and connected side panels extending upward in spaced relation to one another from said pair of edges, each of the side panels having a series of openings therethrough in spaced relation to one another and to the bounding edges of the panel, each of the containers being disposed upon said bottom panel between the side panels and each having substantially opposite side wall portions one of which is disposed adjacent to one of the carrier side panels and the other of which is disposed adjacent to the other side panel of the carrier, each of said container wall portions having an opening in register with one of the openings in the adjacent side panel, a closure member integral with and hinged to its container, each closure member having flap portions adapted to extend over the upper edges of said side panels and downward along the outer side faces thereof, and means carried by each container closure member flap portion projecting through the adjacent registering openings in the side panel and side wall portions for interlocking the containers and carrier.

8. A unitary package composed of sheet material such as paperboard and comprising a plurality of individual merchandise containers each of hexagonal form and a carrier member common to all of the containers for the simultaneous support thereof, the carrier member including a generally rectangular bottom support panel and connected side panels extending upward in spaced relation to one another from a pair of opposite edges of the bottom panel, each of the side panels having a series of openings therethrough in spaced relation to one another and to the bounding edges of the panel, each of the containers having one wall disposed upon said bottom panel between the side panels and each having substantially opposite side wall portion one of which is disposed adjacent to one of the carrier side panels and the other of which is disposed adjacent to the other side panel of the carrier, each of said container wall portions having an opening in register with one of the openings in the adjacent side panel, a closure member forming a top wall for each container and extending transversely of and outwardly of the upper edges of said side panels of the carrier member, and means carried by each closure member depending along the upper portion of the carrier side panels and projecting through the adjacent registering openings in the side panel and side wall portions for interlocking the containers and carrier.

9. A unitary package of the character described composed of sheet material such as paperboard and comprising in combination, a carrier member formed from a single piece of the material and providing a generally rectangular bottom panel and a side panel extending along and upward from each of a pair of opposite side edges of the bottom panel, each of the side panels having a plurality of openings therethrough located in spaced relation to one another and to the boundaries of the panel,

a flap integral with each side panel at each of said openings therethrough, a plurality of containers each of substantially hexahedral form disposed with a corresponding side of each on the upper side of said bottom panel and with one of a pair of opposite sides extending upward adjacent and substantially parallel to the inner faces of one of said side panels and the other of such pair similarly related to the inner face of the other of said side panels, each container having an integral closure member forming its upper side opposite to said bottom side, an end portion of each closure member extending across and downwardly from the top edge of one of said side panels, a locking flap on each of said closure end portions, one of said pair of sides of each container having an opening therethrough, each container side opening being in register with one of the flaps of the adjacent carrier side panel and with the flap on such container closure portion and such flaps being disposed through such openings.

10. A unitary package of the character described composed of sheet material such as paperboard and comprising in combination, a carrier member formed from a single piece of the material and providing a generally rectangular bottom panel and a side panel extending along and upward from each of a pair of opposite side edges of the bottom panel, each of the side panels having a plurality of openings therethrough located in spaced relation to one another and to the boundaries of the panel, a flap integral with each side panel at each of said openings therethrough, a plurality of containers each of substantially hexahedral form disposed with a corresponding

5
